SUPPORT-ENGAGING BASE FOR DISPLAY
DEVICES

William G. Huber, Hopkins, Minn.

Application November 24, 1937, Serial No. 176,265

3 Claims. (Cl. 248—346)

This invention relates to display devices which are particularly adaptable for use in connection with advertising signs in business establishments, and which may be conveniently placed in a convenient manner to provide a relative rigid support therefor.

One of the objects of the invention is to provide a simply constructed and visibly attractive display device which may be easily and detachably secured to a support, the support itself being, if desired, a fixture of the establishment which is already being put to use for some other purpose.

A further object of the invention is to provide a display device which is adapted to lie flat upon the article utilized to support the same without in any way interfering with the normal use of the support.

A still further object of the invention is to provide a device which is constructed to grip the sides of the element which supports it and which is capable of attachment to supports of varying widths without making any mechanical change in the display device.

Another object is to provide means for supporting the display in various positions relative to its support.

Still a further object of the invention is to construct the support gripping elements of the display device in such a manner that the device can be placed upon a relatively broad supporting surface without gripping the sides thereof and, at the same time, causing the device to rest in a horizontal position without having to alter the article in any manner.

These and other objects and advantages of the invention will more fully appear from the following description made in connection with the accompanying drawings wherein like reference characters refer to the same or similar parts throughout the various views, and in which:

Fig. 1 is a front elevation of my display device secured to a suitable support;

Fig. 2 is a section taken approximately on the line 2—2 of Fig. 1;

Fig. 3 is a section taken approximately on the line 3—3 of Fig. 1;

Fig. 4 is a bottom plan view of a modified form of my invention;

Fig. 5 is a transverse section through the structure shown in Fig. 4, and

Fig. 6 is a transverse sectional view of a still different type of arrangement.

In the particular embodiment of my invention disclosed in the drawings there is illustrated a

body 4 which is preferably formed of wood and may have secured thereto an upright sign back 5 held by countersunk screws 6 and adapted to support in any suitable manner a sign face 5a. As shown in Fig. 2, the sign face is made of glass, but of course the advertising matter may be applied directly to the back 5 by painting thereon, or any other desirable means of constructing the sign itself may be used. As a matter of fact it is not necessary that a sign be placed upon the body 4, but the body may be utilized to support a container for displaying merchandise for sale. It will be noted that the front and ends of the body 4 have a horizontal groove running therearound to receive a decorative metal strip 7 which adds to the attractiveness of the entire device. As best shown in Figs. 2 and 3, the body of the device is provided with a horizontal slot or cut-out 8 which lies between upper and lower surfaces of the block 4 which forms the body and is preferably open only at the back of said block. Retained within the recess or slot 8, as by a screw 9 extending up from the bottom of said body and through said cut-out portion is a resilient spring element including a loop 10 and substantially oppositely extending arms 11. The spring with its loop and arms is so constructed that said arms have a constant tendency to draw inwardly toward the body 4. The outer ends of said arms extend to points adjacent the ends of the body and are provided with downwardly turned end portions 12 which are provided preferably with rubber grip elements 13. To permit insertion of the screws 6 to the position shown in Fig. 2, I provide a pair of openings 14 which extend from the cut-out portion 8 downwardly through the body so that said screws 6 can be inserted through the openings and their heads can be countersunk in the upper portion of the body 4.

Extending downwardly from the forward edge of the body 4 somewhere near the ends thereof are front support gripping elements 15 which are shown to comprise small pieces of metal bent at ninety degree angles and countersunk in the bottom face of said body where they are retained by screws 16.

It is preferred that the lower ends of the gripping elements 15 and the gripping elements 13 terminate on the same horizontal plane so that the display device can be merely rested upon the top of some supporting surface without any gripping action.

It will be seen from the foregoing description that I have provided a display device having a body with flat undersurfaces so that it will rest

flatly upon a smooth topped supporting article such as a cash-register top in a business establishment. The forward rigid gripping elements 15 will engage the front sides of the supporting element, the latter being indicated partially at 17, and the rear resilient gripping elements can be moved laterally away from the body 4 until the forward and rearward gripping elements will engage the front and rear vertical walls of the cash-register or other supporting medium. If the device to which the display is secured should be considerably wider than the display itself, then the arms 11 which are resilient can be swung backwardly considerably further than shown in the full line position in Fig. 3 to the dotted line position indicated in that figure, thereby permitting the use of the display upon supporting media of various widths without making any mechanical change or time consuming adjustment to properly secure the device. The construction, therefore, provides a reasonably made and simply constructed display which is neat and attractive in appearance and requires no fastening means which might injure or deface the store fixture to which it is secured. The fact that it is at all times adapted for use in supports of various widths permits mass production of the device without regard to the support to which individual displays will be ultimately secured.

In the embodiment of the invention shown in Figs. 4 and 5, it will be noted that the resilient gripping elements 18 are fastened within a recess 19 which is open to the bottom of the display body 20. The resilient arms are connected to a suitable spring mechanism 21 similar to that shown in Figs. 1 through 3, and is retained as by a screw 22. It will be noted in Fig. 5 that the downwardly turned ends 23 of the resilient arms 18 are permitted to travel inwardly beneath the body rather than being stopped at the rear edge of the body as in the first described embodiment. In addition the rigid support engaging elements 24 are positioned inwardly from the front edge of the body 20 in suitable slots or cut-outs 25 so that the bottom of the body can rest flatly upon a suitable supporting medium 26 which may be the top of a cash-register, a shelf molding or any other convenient store fixture. Due to the fact that the support-engaging elements lie normally a substantial distance in from the front and rear edges of the body, the latter can be secured to a supporting element which is of considerably less width than that of the body. Naturally the body is adapted to support and display a suitable sign element 27 or some similar device.

In the embodiment shown in Fig. 6 the body 28 supports a sign 29 and is, in turn, detachably

secured to a convenient piece of store furniture 30 by means of rigid engaging elements 31 secured within slots 32. These rigid elements 31 are preferably positioned toward the rear edge of the body 28 where they cooperate with resilient arms 33 which are connected with a coil or other type of spring element 34, the latter being anchored within a horizontal slot or cut-out 35 similar to the cut-out 8 shown in Figs. 2 and 3. With the engaging elements arranged as in Fig. 6, it is possible to secure the horizontal body 28 in such a manner that it will extend considerably beyond the front edge of the store fixture 30 to which it is secured. Of course, if desired, the sign element or other article to be displayed may be positioned at the front edge of the body 28 or may be placed in any satisfactory relation to the body best suited for effective display purposes.

It will, of course, be understood, that various changes may be made in the form, details, arrangements and proportions of the various parts without departing from the scope of my invention.

What is claimed is:

1. In a support engaging base for a display device and the like, a body having a substantially flat bottom contact surface, a rigid support engaging element extending downwardly from said body adjacent one side thereof to a point below said flat bottom surface, said body having a recess therein extending inwardly from a side thereof, a pair of spring tensioned arms having portions anchored in said recess and also having portions swingable out of said recess in a substantially horizontal plane above said flat bottom surface, said arms having ends provided with portions extending downwardly below said flat bottom surface and said arms and their downwardly extending portions being swingable under tension away from said rigid element.

2. A support engaging base for a display device comprising a body having a substantially flat bottom surface for contacting the top of said support, a rigid element secured to said body and extending below said bottom surface to engage a lateral surface of said support, spring arms swingable in a plane substantially parallel to said bottom surface mounted on said body and means extending from said spring arms below said bottom surface to engage a lateral surface of said support opposite said first named lateral surface.

3. In the support engaging base of claim 2, said last-named means comprising downwardly turned portions at the ends of said spring arms and resilient means on said portions to prevent accidental slippage of said arms when gripping a support.

WILLIAM G. HUBER.
